UNITED STATES PATENT OFFICE.

WILLIAM PAUL KOPPE, OF BROOKLYN, NEW YORK, ASSIGNOR TO SCHOLL MANUFACTURING COMPANY, INC., OF CHICAGO, ILLINOIS, A CORPORATION OF NEW YORK.

BUNION-CORRECTIVE APPLIANCE.

1,245,468.

Specification of Letters Patent.

Patented Nov. 6, 1917.

Application filed March 16, 1917. Serial No. 155,193.

To all whom it may concern:

Be it known that I, WILLIAM P. KOPPE, a citizen of the United States, residing at Brooklyn borough, in the county of Kings and State of New York, have invented certain new and useful Improvements in Bunion-Corrective Appliances, of which the following is a specification.

My invention relates to improvements in bunion corrective appliances, and has for its general object to provide a mechanical instrumentality, simple in construction, comfortable to wear, and efficacious in operation, for applying pressure to the great toe to bring the phalanges into, and maintain them in, proper anatomical relation to the first metatarsal, without creating any undue or distressing pressure upon the fleshy portions of the foot contiguous to the first metatarsophalangeal articulation.

It is a fact of general knowledge that in cases of Hallux Valgus and bunion, curative treatment usually demands a mechanical restoration of the great toe from its outwardly-misplaced position, but with minimal irritation to the usually-swollen and highly sensitive tissues contiguous to the great toe joint. These desiderata I attain by means hereinafter described and claimed, as illustrated in the accompanying drawings, wherein—

Figure 1 is a perspective view of an embodiment of my invention in use;

Fig. 2 is a side elevation thereof;

Fig. 3 is a plan view thereof with fragments broken away;

Fig. 4 is a vertical section on line 4—4 of Fig. 3;

Fig. 5 is a section on line 5—5 of Fig. 3;

Fig. 6 is a side view of a modified form of structure;

Fig. 7 is a plan detail thereof; and

Fig. 8 is a section on line 8—8 of Fig. 6.

My improved appliance comprises a relatively stiff lever, generally indicated at 10, having its front end bifurcated to provide upper and lower arms 11 and 12 joined at their outer ends by a pressure web 13 that may engage the outer side (i. e., side toward the outer margin of the foot) of the great toe, said arms being properly shaped to extend above and below the great toe and toward the inner side of the foot to meet in rear of the metatarsophalangeal articulation, at what I will term the fulcrum-area

14 of the lever, said lever thence extending rearwardly a suitable distance, preferably to the neighborhood of the scaphoid bone, and at its rearward end provided with means, as the strap 15, to girdle the foot 60 and apply pressure to the lever.

I believe that I am the first to provide a toe-straightening lever of the character described, having only its fulcrum area and its girdle-connected end disposed along the 65 inner margin of the foot, and that wholly in rear of the metatarsophalangeal articulation, the pressure applying portions comprising arms extending above and below the foot across the line of the great toe and 70 lengthwise to near its extremity, and there connected by a pressure web that coacts with the outer side of the great toe.

In specific construction, some features of which I may hereafter claim for their particular advantage, I prefer that the metallic portions of the lever be made of a single piece of sheet metal formed to provide an underfoot extension 17 curved transversely to pass under the instep and to aid in giving 75 very definite position to the lever by substantially preventing vertical displacement of its rearward or pressure-receiving end. To this extension the band 15 may be attached, the band being preferably of heavy 80 webbing that may encircle the foot either directly around the instep or, as shown in Fig. 1, with a loop around the ankle. A buckle 15' typifies any suitable means for 85 securing adjustment of the strap to regulate 90 the pressure brought to bear on the pressure-receiving end.

The solid portion of the lever is preferably rather broad, and suitably curved in sectional contour for substantial conformity 95 to the usual curvatures of the inner side of the foot, and the two arms 11 and 12 are sprung from the forward portion of this body in gradual curves, widest spread just in front of the fulcrum area from which 100 they spring, where they pass above and below the great toe joint. These arms twist as they progress forwardly so that near their extremities they lie nearly horizontal, in an approximation to parallelism, their curvatures throughout being fashioned for conformity with the foot of the wearer. In practice I prefer that the metal employed in the lever shall be rather ductile, and quite thin, so that with pincers or strong 110

hand pressure they can be bent by the user for most comfortable precision in fit.

The pressure web 13 as shown in Figs. 1 and 2 may be an integral part of the metal structure, blanked out in suitable size and sharply bent back as shown in Fig. 4 to double the metal on itself, as at 18 so providing a bead-like edge for presentation toward the great toe and stiffening the extremity 10 of the device. In some instances, however, it may be preferable to employ a more flexible pressure web and to this end the construction as shown in Figs. 6 to 8 may be adopted wherein 13' is a pressure web of 15 fabric-webbing, and one end secured to slots 19 in the lower arm 12 and at its other end passing through slots 20 in the upper arm 11, to be held in adjusted position, as by teeth 21 margining one of said slots. Such 20 a modification is of particular utility where the condition of the foot is such that very gradual replacement of the great toe is necessary, since obviously adjustment of the fabric web 13' will enable the girdle band 15 25 always to be snugly drawn without imposing undue pressure on the toe.

It is my preference that all of the metal parts of the structure be protectively covered for the comfort of the wearer, and as 30 illustrated in Fig. 4 I find it to be desirable to cover surfaces that are presented toward the foot with chamois-skin, buck-skin, or other relatively soft material, and the exteriorly presented surfaces with a kid or 35 other smooth surfaced material, these coverings being cemented to the metal and to each other.

It will be understood that while I have described in considerable detail specific 40 embodiments of my invention for purposes of full disclosure thereof, such details are not vital to the embodiment of my invention in its broader aspects, and that many changes 45 may be made in the specific construction without departure from the spirit of my invention and within the scope of the appended claims.

Having described my invention, what I 50 claim is:—

1. A lever structure for exerting restorative pressure on the great toe comprising a body portion adapted to extend along the

inner side of the foot in rear, only, of the metatarso-phalangeal articulation, arms extending forwardly and laterally from said body above and below the foot toward the outer side of the great toe end, a pressure web to engage the outer side of the great toe connecting said arm, and a girdle band engaging the rear portion of the body. 55 60

2. A great toe straightening apparatus comprising a fulcrum portion adapted to engage the inner side of a foot in rear of the great toe joint, body portions extending rearwardly therefrom, arms extending from 65 said fulcrum portion forwardly and laterally across the line of the great toe above and below the foot, a pressure web for coaction with the outer side of the great toe connecting the end portions of said arm, and means for exerting pressure on the body 70 end of said lever to press the latter toward the foot.

3. Apparatus for straightening the great toe comprising a lever plate having a solid portion for coaction with the inner side of the foot and shaped approximately to fit a human foot from a point in rear of the great toe joint to approximately the scaphoid bone, and two integral arms extending above 80 and below the foot, across the line of the great toe substantially to the end of the toe, thereby to leave the toe free as to its inner surface, a pressure web connecting the extremities of the arms to bear against the 85 outer side of the great toe, and a foot girdling band connected with the rear end of the lever. 75

4. A toe straightening lever comprising a body portion having an underfoot extension 90 17 and forwardly and laterally extending arms 11 and 12 arranged to cross the line of the great toe above and below the foot, a web connecting the extremities of said arms to coact with only the outer side of the great 95 toe, and a foot girdling band connected to the rear end of the body.

In testimony whereof I hereunto set my hand in the presence of two subscribing witnesses.

WILLIAM PAUL KOPPE.

In the presence of—

SEWARD DAVIS,
OLIVER WILLIAMS.
